STUDIO COUCH BACK REST

Edward E. Woller, Kenosha, Wis., assignor to
 Simmons Company, New York, N. Y., a corporation of Delaware

Application September 20, 1937, Serial No. 164,656

8 Claims. (Cl. 5—59)

This invention relates to an improved back rest construction for employment on a couch such as a studio couch and which has for its main object the provision of a back rest which 5 may be quickly and easily displaced so as to clear the sleeping surface of the couch structure.

Further objects of the invention are to provide a back rest construction which may be adjusted to an out-of-the-way position but without wholly 10 disassembling the back rest from the couch structure; to provide a back rest structure which although adjustable as indicated is sufficiently rigid when in its operative back rest position to efficiently serve its back rest function; to provide 15 a back rest structure such as indicated which will be easy and relatively inexpensive to manufacture, and in general, it is the object of the invention to provide an improved back rest structure of the type indicated.

20 Other objects and advantages of the invention will be understood by reference to the following specification and accompanying drawings (2 sheets), wherein there is illustrated a studio couch structure embodying a selected form of the improved back rest.

In the drawings:

Fig. 1 is a perspective of a studio couch equipped with the improved back rest.

Fig. 2 is a section on a vertical plane indicated by the line 2—2 of Fig. 1.

Fig. 3 is a section in a plane indicated by the line 3—3 of Fig. 1.

Fig. 4 is a view similar to Fig. 3, but showing the back rest in an adjusted position.

Fig. 5 is a section on the line 5—5 of Fig. 3.

Fig. 6 is an end view of a studio couch structure equipped with the improved back rest, and

Fig. 7 is an end view similar to Fig. 6, but showing the studio couch structure extended to 40 provide a bed of superior width and having the back rest structure adjusted to an out-of-the-way position.

Referring now to the drawings, the couch structure illustrated in Fig. 1 comprises a main outside structure 10 having a mattress or cushion 11 thereon. The details of construction of the couch section proper are not important in connection with the present invention since the invention proper, as already indicated, relates 45 particularly to the back rest construction which may be applied to any desired form of couch structure.

As shown in Fig. 1, the back rest construction includes arm rest members 12 having integrally connected depending front and rear legs 13 and

14 disposed on the outside of the ends of the couch structure proper and suitably rigidly secured thereto. The rear leg portion 14 has connected to it a back rest proper which comprises end members 15, 15 and upper and lower longitudinal members 16 and 17 respectively. 5

In this instance, the end members 15 and the upper longitudinal member 16 are formed integrally of tubing bent to shape. The member 17 may also be of tubing but it is adjustably connected to the end members 15, 15 and the latter are pivotally connected to the rear legs 14, 14 of the arm rest units. 10

The end members 15, 15 of the back rest structure are provided with flat, downwardly extending straps such as indicated at 18, the same being welded or otherwise rigidly secured to the end members 15. The lower ends of the extensions 18 are pivotally connected as indicated at 19 to the rear leg portions 14 of the arm rest units. 15 20 The upper ends of the legs 14 may be suitably capped as indicated at 20 and the lower ends of the end members 15 may be similarly capped as indicated at 21 to finish the ends of the respective parts 14 and 15. A stop 34 may be 25 provided for engaging the extensions 18 to limit upward and forward swinging of the back rest structure.

The lower longitudinal member 17 is provided at its ends with transversely extending legs or 30 arms 22, the same being welded or otherwise rigidly secured to the said member 17. At their free ends, the arms 22 are pivoted as indicated at 23 to the end members 15. As shown, the pivot connection 23 is in this instance made with the upper end portion of the strap member 18 35 which may be of somewhat heavier metal than the tubular end member 15. Thus it will appear that the longitudinal member 17 may be rocked from its normal position as shown in full lines 40 in Figs. 1, 2, 3 and 5, to an elevated position as shown in dotted lines in Figs. 2 and 3.

For locking the back rest structure in its normal back rest position, there is provided a latch bar 24 which is pivoted as indicated at 25 to the 45 arm 22, a short distance from the pivot mounting 23 of the latter. The lower end of the latch bar 24 is provided with a detent or stud 26 which projects laterally from the latch bar through an elongated opening 27 in the extension 18 and 50 into a notch or slot 28 provided in the upper end portion of the leg part 14. The width of the slot 27 and of the notch 28 is, as best indicated in Fig. 4, just sufficient to permit the pin or stud 26 to move therein. It will be apparent 55

that when the parts are in the position indicated in Fig. 5, the back rest structure will be locked in its upwardly extending operative position since the extension 18 is held against rocking on its pivot 19 by the stud 26.

When it is desired to adjust the back rest to an out-of-the-way position, the lower longitudinal member 17 thereof is rocked forwardly and upwardly as indicated by the arrows 29 and 30 (Fig. 3), during which movement the pivot pin 25 acts as a crank pin swinging about the pivot 23 and lifts or raises the latch bar 24 to thereby withdraw the locking stud 26 from the notch 28. The lower end portion of the leg 15 is suitably notched as indicated at 30, to receive the locking stud 26 when it is withdrawn from the notch 28 in the leg structure 14.

The latch bar 24 is provided adjacent its upper end with an extension or lip 31 which is adapted to engage the pivot pin 23 when the back rest is in operative position. Such engagement serves to limit downward swinging movement of the lower longitudinal back rest member 17 and to hold it in its predetermined operative relation to the upper back rest member 16. As shown in the present disclosure, the member 17 is normally located in the plane of the back rest members 15, 15, and 16, although it will be understood that other relationships may also be employed if preferred. The latch bar 24 is further provided with a notch or recess 32 which is adapted to receive the pivot pin 23, as clearly shown in Fig. 4, when the back rest member 17 is rocked to its upwardly adjusted position for disengaging the locking stud 26 from the locking notch 28. Such engagement of the latch bar 24 with the pivot pin 23 also serves to limit the swinging movement of the lower member 17 of the back rest about its pivot 23.

The described back rest structure may be useful in connection with a single couch structure in that when a couch structure is to be used for sleeping purposes, it is perhaps desirable that the normal back rest structure be displaced so as to fully clear the sleeping surface of the couch. However, the described folding back rest structure has particular utility in connection with studio couch structures which normally comprise a main outer section, of which the section 16 may be typical and an inner section which is adapted to be housed within the main or outer section, when such inner section is not desired for sleeping purposes. Such inner section may be of either the collapsible or non-collapsible variety, both of which are well known in the art. In Fig. 7, there is more or less diagrammatically illustrated the relationship of an outer couch structure, such as typified by the main couch structure 10, and a collapsible couch unit 33 designated in its entirety. When the collapsible couch unit 33 is uncovered and elevated to cause its top surface to be co-planar and contiguous with the sleeping surface of the main unit, it provides a bed structure of superior width. By displacing the back rest structure to a depending position closely adjacent the back of the main structure and below its sleeping surface, the full width of the combined couch sections become freely available for occupancy. As shown in Fig. 6, the collapsible couch section 33 is collapsed and housed within the main or outer couch section 10 and the back rest structure is restored to its normal back rest position.

It will be apparent that the rear leg members 14 of the arm rest units constitute in effect

brackets or posts to which the back rest structure is pivoted. So far as the operation of the back rest structure is concerned, the arm rests proper are not required. It will furthermore be understood that the disengageable locking means described is provided at both ends of the structure so as to rigidly maintain the back rest in operative position. The second longitudinally extending member 17 serves to interconnect the locking devices for simultaneous adjustment by a single manual operation, namely, the swinging or rocking of said second longitudinal member about its pivot mountings.

The described structure is simple and easy to operate. It involves a simple rocking of the lower longitudinal back rest member 17 to permit folding of the upwardly extending back rest structure to a lowered position wherein it is below the sleeping surface of the couch structure and adjacent the rear side thereof. In this position it offers no obstruction to positioning an auxiliary couch section closely adjacent the main structure or the positioning of the main structure adjacent a wall if desired. The parts required for the described structure are of simple forms and relatively inexpensive to manufacture and assemble, so that the cost of providing the described foldable back rest structure is within practical limits with reference to commercial considerations.

Changes in the described structure may be made without departing from the spirit of the invention, the scope of which should be determined by reference to the following claims, the same being construed as broadly as possible consistent with the state of the art.

I claim:

1. In a couch structure, a back rest comprising a longitudinally extending member and end members extending downwardly from the opposite ends of said longitudinal member, rigid posts extending upwardly from said couch structure, means pivotally connecting said back rest end members to said posts so as to permit folding of said back rest downwardly to substantially inverted position adjacent the back of the couch and with said longitudinal member below the sleeping surface of the couch, means for locking said end members to said posts against rocking movement about said pivotal connections therebetween, and means movably mounted on said back rest for disengaging said locking means to thereby permit such rocking movement.

2. In a couch structure, a back rest comprising a longitudinally extending member and a pair of end members extending downwardly adjacent the opposite ends of said longitudinal member, posts extending upwardly from the couch structure into juxtaposed relation to said end members, depending extensions rigid with said end members and extending into overlapping relation to the respectively adjacent posts and pivotally connected adjacent their lower ends to said posts, disengageable means for interlocking said extensions and posts in spaced relation to said pivotal connection for preventing rocking movement of said back rest structure about the pivotal connections between said extensions and posts, and interconnected means for effecting simultaneous dis-engagement of said interlocking means to permit said rocking movement, said interconnected means comprising a second longitudinal member, arms extending laterally from the ends of said second longitudinal member and pivotally connected adjacent their free ends to said

back rest end members, and connections between said arms and said interlocking means, said connections being operable to effect disengagement of said interlocking means as an incident to rocking movement of said second longitudinal member about said pivotal connections between said arms and end members.

3. In combination in a couch of the class described, a back rest structure comprising a longitudinal member and end members extending downwardly adjacent the opposite ends of said longitudinal member, posts extending upwardly from the couch structure into juxtaposed relation to said end members, extensions depending from said end members pivotally connected adjacent their free ends to said posts, whereby said back rest structure is foldable from operative back rest position to an inoperative position depending from said pivotal connections, disengageable means for interlocking said extensions and posts in spaced relation to said pivotal connections to prevent said rocking movement of the back rest structure, said disengageable means comprising studs and said posts and extensions having openings for said studs, and means carried by said back rest structure for effecting simultaneous disengagement of said studs from the notches in said posts so as to permit said rocking movement, said last mentioned means comprising a second longitudinal member, arms extending laterally from the ends of said second longitudinal member and pivotally connected adjacent their free ends to said end members of the back rest structure, whereby said second longitudinal member and arms are adapted to be rocked about the pivotal connections of the latter with the said end members, and link connections between said arms and said studs for effecting said withdrawal of said studs incident to said rocking movement of said second longitudinal member.

4. In combination in a couch of the class described, a back rest structure comprising a longitudinal member and end members extending downwardly adjacent the opposite ends of said longitudinal member, posts extending upwardly from the couch structure into juxtaposed relation to said end members, extensions depending from said end members pivotally connected adjacent their free ends to said posts, whereby said back rest structure is foldable from operative back rest position to an inoperative position depending from said pivotal connections, disengageable means for interlocking said extensions and posts in spaced relation to said pivotal connections to prevent said rocking movement of the back rest structure, said disengageable means comprising studs and said posts and extensions having openings for said studs, and means carried by said back rest structure for effecting simultaneous disengagement of said studs from the notches in said posts so as to permit said rocking movement, said last mentioned means comprising a second longitudinal member, arms extending laterally from the ends of said second longitudinal member and pivotally connected adjacent their free ends to said end members of the back rest structure, whereby said second longitudinal member and arms are adapted to be rocked about the pivotal connections of the latter with the said end members, and link connections between said arms and said studs for effecting said withdrawal of said studs incident to said rocking movement of said second longitudinal member, said links being provided with

portions adapted to engage the pivotal connections between said arms and end members for limiting rocking movement of said second longitudinal member and arms.

5. In combination with a couch of the class described, a back rest structure comprising a longitudinal member and end members extending downwardly from the opposite ends of said longitudinal member, means pivotally connecting the lower ends of said depending end members to said couch so as to permit the folding movement of said longitudinal member from operative back rest position to inoperative position below the sleeping surface of the couch and adjacent the rear thereof, disengageable means associated with each pivotal connection of the back rest structure to the couch for locking said back rest structure against such folding movement, and means interconnecting said locking means for simultaneous disengagement by a single operation, said last mentioned means comprising a second longitudinal member having laterally projecting end extensions pivotally mounted adjacent their free ends on the end members of said back rest structure, whereby said second longitudinal member is adapted to be rocked from a predetermined normal position wherein it constitutes a portion of the back rest structure to a displaced position as an incident to which its said end extensions are caused to swing about their pivotal connections with said back rest end members, and operative connections between the respective end extensions and said locking means.

6. A main couch section having a back rest cushion supporting frame adjustably mounted on the couch so as to be movable from normal back rest position to inoperative position below the sleeping surface of the couch and adjacent the rear thereof, said frame comprising upper and lower longitudinally extending members, the lower member being mounted in said back rest so as to be movable to a relatively elevated position therein, whereby, when the back rest is disposed in said inoperative position, said lower member is disposed sufficiently below the surface of the couch to facilitate the positioning of an auxiliary couch adjacent the back of the main couch to form a double bed.

7. In combination with a couch structure, a back rest comprising a longitudinally extending member and end members, respectively, extending downwardly from the opposite ends of said longitudinal member, said end members being pivotally connected adjacent their lower ends to said couch structure so as to permit the back rest to be folded to substantially inverted position with said longitudinal member disposed adjacent the rear of the couch structure below the top thereof, disengageable means for interlocking each of said end members and couch structure to maintain the back rest in normal back rest position, and means for effecting simultaneous disengagement of said locking means comprising a second longitudinal member normally disposed substantially below said first mentioned longitudinal member and operatively connected at its ends with said interlocking means, said second longitudinal member being movable from normal position in said back rest to a relatively elevated position, wherein said member, when the back rest is inverted, is disposed below the surface of the couch structure sufficiently to facilitate the positioning of an auxiliary couch adjacent the back of the structure to form a double bed.

8. A couch section having a back rest cushion

supporting frame adjustably mounted on the couch so as to be movable from normal, upwardly extending, back rest position to inverted position adjacent the rear of the couch, said frame comprising upper and lower, longitudinally extending members, the lower member being mounted in the back rest so as to be movable a substantial distance toward the upper member whereby

the back rest is adapted to be disposed in said inverted position with said lower member adjusted to a position sufficiently below the surface of the couch to facilitate the positioning of another couch section adjacent the back of the first mentioned couch section to form a double bed.

EDWARD E. WOLLER.
